(57) **CLAIM**

The ornamental design for forceps, as shown and described.

DESCRIPTION

FIG. 1 is a top side, slightly right side and perspective view of forceps showing my new design in a closed condition; FIG. 2 is a top side, right side and perspective view thereof; FIG. 3 is a bottom side, left side and perspective view thereof; FIG. 4 is a top side, right side, perspective view thereof in a partially open position;

FIG. 5 is a bottom side, left side, perspective view thereof; FIG. 6 is a front end, left side, top, perspective view thereof in a fully open position;

FIG. 7 is a top side, right side perspective view of one forcep of the pair of forceps showing my new design;

FIG. 8 is a bottom side, right side perspective view of the other forcep of the pair of forceps showing my new design;

FIG. 9 is a bottom side, left side, perspective view of the pair of forceps arranged oriented for being assembled together; and,

FIG. 10 is a right side, rear end, top perspective view of the pair of forceps arranged oriented for being assembled together.

The broken line showing immediately adjacent the shaded areas represents boundaries to the claimed design and forms no part of the claimed design.
